UNITED STATES PATENT OFFICE.

FREDERIC E. BALDWIN, OF NEW YORK, N. Y.

ACETYLENE LAMP AND GENERATOR.

1,070,000.

Specification of Letters Patent. Patented Aug. 12, 1913.

Application filed May 3, 1910. Serial No. 559,071.

To all whom it may concern:

Be it known that I, FREDERIC E. BALDWIN, a citizen of the United States, residing at New York, county of Richmond, and 5 State of New York, have invented certain new and useful Improvements in Acetylene Lamps and Generators, of which the following is a full, clear, and exact description.

This invention relates to acetylene lamps 10 and generators, reference being had to the accompanying drawings, in which—

Figure 1 represents a central vertical section through a lamp embodying the invention, and Fig. 2 a detail illustrating the 15 means for attaching the cover to the gas tube.

A is a water tank, to the bottom of which is attached a cleaning rod B.

C is the carbide container having a gas outlet D.

In the bottom of the container C is fastened a tube E, terminating at its lower end in a flaring mouth F. The tube E which surrounds the rod is slightly larger than rod 25 B, so that only the required amount of water can pass up the tube and enter the carbide container. On top of the water tank A is placed a cover G having a tube or collar H, closely fitting gas outlet D, otherwise 30 excess gas escaping between the collar and the outlet might ignite and by flashing back cause an explosion in the water tank A when the container is agitated. The cover G may be securely fastened by any suitable 35 lock.

I have found it desirable in many cases to provide additional means for maintaining a steady flame for a long time. This may be done by means of an auxiliary water tank 40 O, attached to or depending from the cover G, and having a water filler cap S with a water outlet R. In the water tank is placed an air inlet pipe T extending to the top of the water tank. By filling the water tank 45 A with water so that it just covers the air inlet pipe T, no air can enter into the water supply O, and therefore no water can run out. It will be understood, of course, that the auxiliary tank is hermetically sealed except for the inlet pipe.

As soon as the carbide in container C has used up sufficient water to uncover the air inlet pipe T, the air will enter into the water tank O, allowing the water to run out 55 through the vent R. This continues until the water level in the water tank A has

again closed the orifice of the air inlet pipe T, which at once causes the water to cease running out of the water tank O. In this manner, a constant water level is always 60 maintained in the water tank A, which therefore maintains a constant pressure of water, resulting in a steady flame. Where, as in the particular construction illustrated, the inlet pipe T opens into the main tank 65 above the bottom of the auxiliary tank, the main tank will be filled up to and slightly above the bottom of the auxiliary tank. This construction has the advantage that there is no place for the gas to collect in 70 case, due to excessive gas generation, gas is forced back through the pipe E and into the tank A. There is, therefore, no liability of explosion due to a collection of gas in the lamp. Surrounding the rod B at the bottom I place a resilient gasket L of sufficient 75 size to close the opening of the water tube E, and on the gas outlet D I place a stud M. In the collar H I place a bayonet slot N, Fig. 2, in which the stud M locks. The carbide is placed in the container C and a suitable amount of water placed in the water tank A. The carbide container C is now placed in the water tank A and the rod B inserted in the tube E, such insertion being 80 greatly facilitated by flaring the lower end of tube E, as shown at F. The cover G is fastened in place, and by pressing down on the gas orifice D the gasket L is compressed sufficiently to prevent any water entering 85 the carbide container, and is held in this compressed position by locking stud M in the slot N. The generator can remain thus charged until wanted for use, when by unlocking the stud M and resting it on the 90 top of the collar N the water can freely enter the tube E so long as desired. Water entering the tube E generates the gas. During this operation the carbide may cake around the orifice of tube E, or sediment 95 may enter the tube E and prevent the flow of water. It is necessary, therefore, to occasionally free this accumulation of dirt so that the water can flow freely, and this is easily accomplished by taking hold of the 100 gas outlet D and slightly raising and lowering the carbide container, whereby rod B breaks up any accumulation of slaked carbide or other obstruction.

While the construction illustrated is intended to be used with the auxiliary water tank as described, in certain cases this auxil-

iary tank may be removed where the advantages of an automatic maintenance of the water level in the tank are not to be utilized. When the auxiliary tank is not 5 employed the cleaning rod B before referred to acts to steady or maintain in a fixed position the carbide container. If the container is not full of carbide it may not be stable in position in the water tank, that is, it may tip or rock out of position, this being specially true if, as is sometimes done, a hose is connected to the gas outlet D.

What I claim as my invention is:

1. In an acetylene generator, a water tank 15 having a cleaning rod or stirrer attached to and projecting upward from the bottom of the same, a movable carbide chamber set into the water tank, a water tube projecting upwardly into the carbide chamber through 20 which the cleaning rod passes, and a gas outlet from the carbide chamber.

2. In an acetylene generator and lamp, the combination of an inclosing receptacle, provided with an upwardly projecting cleaning 25 rod, a carbide chamber set into said inclosing receptacle and provided with a tube upwardly projecting from its bottom and surrounding the said cleaning rod, a gas tube extending upwardly from the said carbide 30 chamber and made integral with the cover thereof, and a water-supply chamber affording an inclosed passage for said gas tube and provided with an outlet into said inclosing receptacle and with means for automatically discharging water thereinto when 35 the level of the water in said receptacle falls below a predetermined level.

3. In an acetylene generator or lamp, the combination of a carbide container having a 40 water tube extending upwardly from the bottom said tube being provided with a flaring orifice at its lower end, and a water tank in which said container is placed, said water tank being provided with a cleaning or stirring rod which is attached to its bottom and which projects through said water tube.

4. In an acetylene generator, the combination of a carbide container having a water tube extending upwardly from the bottom 50 and having a flaring orifice at its lower end, and a water chamber into which said container is placed, said water chamber being provided with an upwardly extending rod

projecting through said orifice and water 55 tube, said rod being attached to the bottom of said water chamber and provided with a resilient gasket upon which said flaring orifice may be seated.

5. In an acetylene generator or lamp, the 60 combination of a water tank, a stirring rod attached to and projecting upward from the bottom of the same, a carbide container in said water tank and provided with a water inlet tube extending upward from its bottom 65 through which tube said stirring rod projects, and means upon said stirring rod for controlling said water inlet.

6. In an acetylene generator, the combination of a water tank, a carbide chamber and 70 an auxiliary reservoir, said auxiliary reservoir being provided with an air inlet extending from a point near the bottom nearly to the top thereof, and a water outlet so arranged that the water level in the water tank 75 cuts off said air inlet so as to prevent discharge from said auxiliary reservoir, substantially as described.

7. In an acetylene lamp or generator, and in combination, a main water tank, a superimposed auxiliary water tank provided with a water delivery opening leading to the main tank, an air inlet tube for the auxiliary tank, said tube having its mouth located above the bottom of the auxiliary tank and 80 in such position that it will be closed by the water in the main tank when said water has reached a predetermined level, the auxiliary tank being hermetically closed except for 85 said inlet tube, and a carbide container in the 90 main tank, said container being provided with means for admitting water thereto.

8. In an acetylene generator, a water chamber, a carbide chamber, a gas tube connected to and projecting upwardly from the 95 carbide chamber, an auxiliary water chamber having a substantially centrally inclosed passage for the gas tube, and means for controlling the flow of water from said water chambers to the carbide chamber by 100 the reciprocation of the latter chamber.

In testimony whereof I affix my signature in the presence of two subscribing witnesses.

FREDERIC E. BALDWIN.
